UNITED STATES PATENT OFFICE.

JOHN E. PREST, OF MELROSE, MASSACHUSETTS.

THREAD GUIDING AND SUPPORTING MEANS FOR SPINNING AND TWISTING MACHINES.

No. 863,218.

Specification of Letters Patent.

Patented Aug. 13, 1907.

Application filed September 21, 1906. Serial No. 335,548.

To all whom it may concern:

Be it known that I, JOHN E. PREST, a citizen of the United States, residing in Melrose, county of Middlesex, and State of Massachusetts, have invented an improvement in Thread Guiding and Supporting Means for Spinning and Twisting Machines, of which the following description, in connection with the accompanying drawing, is a specification, like letters on the drawing representing like parts.

This invention has for its object to improve the class of thread guide supporting means shown in U. S. Patent No. 758,933, dated May 3, 1904. In that patent and others of which it is a type, the inner end of the guide eye at the underside of the finger board is covered by a shield or guard held in operative position by a bolt, flanges at the opposite edges of the shield contacting with the under side of the finger board. The finger board in practice has to be stopped in its operative or horizontal position, and stopping of the finger board has been effected in various different ways.

In accordance with my present invention, I have, by a change in the shape of the shield also made it operate as a down stop for the finger board.

Figure 1 in front elevation shows part of a roller beam and thread board, with two finger boards, one of the latter being turned up, and Fig. 2 is a section on the line x , Fig. 1, but with the finger board at the left turned down.

In the drawing, A represents part of the usual roller beam, B part of an angular thread board presenting at its front side a flange B' and connected to the roller beam by hinges b, and the roller beam has a stop a to arrest the thread board in its horizontal or operative position. The finger boards C are of sheet metal bent to present side flanges 2, 4 and an end flange 3, the sheet metal forming the finger board being bent at its inner end opposite the flange 3 to form circular eyes 5. The eyes 5 are separated to embrace a hinge member D slotted at d to receive a screw d' that may be inserted through a hole in the downturned flange of the thread board where, see Fig. 2, a nut 6 is applied to said screw. The shank of the thread guide E is passed through the flange 3, and said shank, see Fig. 1, is covered by a stop shield F, the latter being confined to the finger board by a bolt and nut in usual manner.

In accordance with my invention I have so shaped the stop shield that it presents flanged side edges and a

tail piece f extended and offset to cross said rod G, 50 the end of the tail piece contacting, said tail-piece serving to position the upper sides of the boards in the horizontal plane of the top of the thread board, said tail piece, as herein represented, contacting with the hinge member D when the finger board occupies its 55 horizontal or operative position, see Fig. 2, and forms a down stop for the finger board. The effective strength of the stop shield is increased by the contact of its outer end, see Fig. 1, with the flange 3 of the finger board. When about to assemble the parts and support the finger boards on the thread board, the finger board suspending rod G will be thrust through say the right hand ear 5 of each finger board, then through the eye at the upper end of a series of rod sustainers D, then through the other or left hand eye 5 of the 60 finger board, one after the other. This done, the hinge members are placed against the front side of the thread board and the screws d' are inserted in the slots d and the finger boards and rod sustainers are then adjusted longitudinally on said rod, said slots d 65 permitting, and the finger boards having been adjusted to bring the guide eyes of each finger board into proper operative relation to the spindles, then the screws will be tightened to hold the rod sustainers and finger boards in their true operative relation. 70

Having described my invention, what I claim as new and desire to secure by Letters Patent is:—

1. In apparatus of the class described, a thread-board, a series of independent hinged members connected with said thread-board, a series of finger boards mounted to 80 turn about said shaft, a guide-eye for each finger board, and a stop shield connected with each finger board and co-acting with said guide-eye, each stop shield having a tail-piece prolonged and off-set to cross the axis of said shaft and serve as a stop to maintain said finger boards in their 85 horizontal positions.

2. In apparatus of the class described, a thread-board, a series of independent hinged members connected with said thread-board, a series of finger boards mounted to turn about said shaft, a guide-eye for each finger-board, and a 90 stop shield formed of sheet metal presenting side flanges and having a tail-piece off-set and prolonged beyond said flanges sufficiently to cross the axis of said shaft, the end of each tail-piece meeting a hinged member when the finger boards occupy their horizontal operative positions. 95

In testimony whereof, I have signed my name to this specification, in the presence of two subscribing witnesses.

JOHN E. PREST.
